EXTENSIBLE LENGTH LEVEL

Burley L. Parham, Southport, Ind.

Application July 7, 1944, Serial No. 543,876

5 Claims. (Cl. 33—211)

This invention relates to a level indicating device which may be extensible in length whereby the level may ordinarily be carried about in a contracted length condition and then be extruded from either or both ends to reach over longer areas than when in the contracted length condition to secure greater accuracy in the level indication. The invention further provides for an extremely simple and unique construction to achieve the above indicated results, all of which will become more apparent to those versed in the art in the following description of the invention as illustrated in the accompanying drawing in which,

Fig. 1 is a view in side elevation and partial section of a structure embodying the invention in a partially extended length condition;

Fig. 2, a view in top plan;

Fig. 3, a view in transverse vertical section on the line 3—3 in Fig. 1;

Fig. 4, a view in transverse section on the line 4—4 in Fig. 2; and

Fig. 5, a detail in partial section on the line 5—5 in Fig. 4.

Like characters of reference indicate like parts throughout the several views in the drawing.

A generally rectangular body in the nature of a box 10 is provided with a spirit level tube 11 positioned along an upper edge thereof to make the bubble 12 visible through a window provided in the top wall of the box.

From each end of the box 10 flexible concave-convex tapes 13, 14 and 15, 16 (two from each end) may be pulled therefrom. Between the outer ends of these respective pairs of tapes 13, 14 and 15, 16 are fixed spacing blocks 17 and 18. By reason of the tapes being carried by the box 10 to have their extensible lengths therefrom with the concave sides presented on their opposite faces, and tying the outer ends of the pairs together, a fairly rigid extensible assembly is created.

Each of the tapes 13, 14, 15 and 16 is in the shape of the usual and well known steel measuring tape carried within a housing to be spring returned. The same spring return mechanism is employed in combination in the present invention whereby each pair of tapes may be simultaneously returned to their retracted length conditions independently of the other pair. To achieve that construction, the box 10 carries in one end, referring now to the left hand side as shown in Fig. 1, two separate compartments 19 and 20 within which are coiled respectively the tapes 13 and 14, and from which those tapes

may be withdrawn through top openings whereby the two tapes may be pulled from the box 10 in parallel relation one with the other and with their extreme outer edge portions in the same planes respectively as the top and bottom walls of the box 10.

The tape 13, within the compartment 19, is coiled around a spring containing drum 40 to which the inner end of the tape 13 is attached at the point 21, Fig. 1.

Within the spring drum 20 is coiled spring 22 fixed by one end to the drum and by its other end to a center post 23 fixed to the box 10. Thus when the tape 13 is pulled from the compartment 19, the spring 22, being so wound, is wound up tighter for the purpose of eventually returning the tape 13 upon the release of a ratchet mechanism. This mechanism consists of a rod 24, Fig. 4, extending down through the hollow post 23 to strike a bar 25, Fig. 5, which extends across through slots provided in the post 23 and connects with a plate 26 normally urged up against the underside of the spring drum 40 by means of the coil spring 27 surrounding the post 23. The plate 26, Fig. 5, is notched out to engage with a plurality of tongues 47 that are pushed downwardly from the floor of the drum 40. The engagement of the plate 26 with these tongues 27 is such that when the return spring 22

is wound by pulling out the tape 13 the drum will be engaged in whatever position it may be when pulling on the tape 13 is stopped. Then to return the tape 13 to its coiled position within the compartment 40, pressure on the rod 24 will carry the plate 26 out of engagement with the tongues 27 to permit the drum to revolve under the return pull of the spring 22. All of this is a standard construction and operation as found in the usual spring return steel measuring tape.

The same construction as above described is employed for returning the other tapes 14, 15 and 16 to their retracted length positions within their respective compartments provided in the box 10. Therefore, each of these mechanisms, four in all, one in each corner of the box 10, need not be described in detail since each is a duplicate of the other.

Since there are two of these tape return mechanisms at each end of the box 10, one for each tape to be extended therefrom, and since both tapes are pulled from the box in unison by reason of their inter-engagement with the respective tie bars 17 and 18, both return mechanisms should operate in unison in order to return the two tapes at the same rate of speed. To accom-

plish this result, as indicated in Fig. 4, a button 28 is provided to extend through the side wall of the box 10 from a central point where it is secured to an operating bar 29, the ends of which bar respectively press the push rods 24 and 30. The rod 30 corresponds in its function to that of the rod 24 in releasing the spring drum 31 for return of the tape 14. Therefore, by pushing on the button 28, both springs are released simultaneously for return of the tapes 13 and 14 on the one end. The button 32, Fig. 1, toward the other end of the box performs a like function in respect to the return of the tapes 15 and 16. Therefore, either pair of tapes 13, 14 or 15, 16 may be returned at will independently of return of the other pair.

In use, the level may be employed in restricted length conditions whereby the tapes will all be retracted within the box 10, or where the length of the surface permits, both pairs of tapes may be pulled from the ends of the box 10. In each instance, the tape will be for all practical purposes an extension of the face of the box 10 and sufficient rigidity will be presented to permit the proper indication of degree of levelness of the 25 surface or points being tested.

While I have herein shown and described my invention in more or less minute detail in one particular form, it is obvious that structural variations may be employed without departing from the spirit of the invention, and I, therefore, do not desire to be limited to that precise form beyond the limitations as may be imposed by the following claims.

I claim:

1. The combination of a body; a level indicating device carried by the body along one edge portion; a convexo-concave tape carried by the body normally in a coiled condition; said body having an opening at one end thereof through which said tape may travel; means carried by the body for positioning said tape to leave said coil by its edges substantially in the same plane as an edge face of said body, the concave side of said tape being presented outwardly in relation to said body face; a second like tape carried normally in a coiled condition to have an end leaving the body through an opening therein adjacent an edge face opposite said first face to have the tape edges in substantially the same plane therewith and the tape end directed the same as that of the first tape; both of said tapes being extendible from said body as spaced apart, free cantilever members; and a spacer member interconnecting and confined to the outer ends only of said tape externally of said body, whereby both tapes may be extended simultaneously from said body.

2. The combination of a body; a level indicating device carried by the body along one edge portion; a convexo-concave tape carried by the body normally in a coiled condition; said body having an opening at one end thereof through which said tape may travel; means carried by the body for positioning said tape to leave said coil by its edges substantially in the same plane as an edge face of said body, the concave side of said tape being presented outwardly in relation to said body face; a second like tape carried normally in a coiled condition to have an end leaving the body through an opening therein adjacent an edge face opposite said first face to have the tape edges in substantially the same plane therewith and the tape end directed the same as that of the first tape; both of said tapes

being extendible from said body as spaced apart, free cantilever members; and a spacer member interconnecting and confined to the outer ends only of said tape externally of said body, whereby both tapes may be extended simultaneously from said body; and means releasably fixing said tapes in any of their extended positions; and spring means for returning the tapes to said coiled conditions.

3. The combination of a body; a level indicating device carried by the body along one edge portion; a convexo-concave tape carried by the body normally in a coiled condition; said body having an opening at one end thereof through which said tape may travel; means carried by the body for positioning said tape to leave said coil by its edges substantially in the same plane as an edge face of said body, the concave side of said tape being presented outwardly in relation to said body face; a second like tape carried normally in a coiled condition to have an end leaving the body through an opening therein adjacent an edge face opposite said first face to have the tape edges in substantially the same plane therewith and the tape end directed the same as that of the first tape; both of said tapes being extendible from said body as spaced apart, free cantilever members; and a spacer member interconnecting and confined to the outer ends only of said tape externally of said body, whereby both tapes may be extended simultaneously from said body; and means releasably fixing said tapes in any of their extended positions; and spring means for returning the tapes to said coiled conditions.

35 and a control member operable externally of said body associated with said spring means to set up substantially simultaneous operation of both spring means.

4. An extensible length level comprising a body having top and bottom faces; a level indicator carried by the body to be readable from the top face; each of said faces having an opening at corresponding ends; an end wall in the body having ends forming the outer margins of said face openings; means carried by said body for carrying coiled tapes adjacent each of said openings, the tapes being oppositely coiled and so carried that ends thereof may be pulled through said openings over said end wall ends to have the tapes in substantially parallelism and their outer faces substantially in the planes of said faces; both of said tapes being extendible from said body as spaced apart, free cantilever members; and a member interconnecting said tape ends externally of said body and confined to said ends; each of said tapes when extended from their coiled conditions being concavo-convex in cross-section to assume a straight linear direction, one tape being reversed from the other in respect to its cross-section curvature.

5. An extensible length level comprising a body having top and bottom faces; a level indicator carried by the body to be readable from the top face; each of said faces having an opening at corresponding ends; an end wall in the body having ends forming the outer margins of said face openings; means carried by said body for carrying coiled tapes adjacent each of said openings, the tapes being oppositely coiled and so carried that ends thereof may be pulled through said openings over said end wall ends to have the tapes in substantially parallelism and their outer faces substantially in the planes of said faces; and a member interconnecting said tape ends externally of said body; each of said tapes

when extended from their coiled conditions being concavo-convex in cross-section to assume a straight linear direction, one tape being reversed from the other in respect to its cross-section curvature; and a pair of tapes carried in like manner to be extensible from the opposite end of said body; a member interconnecting the outer ends of said second pair of tapes externally of said body; whereby both sets of tapes may be withdrawn as to desired lengths from said body to position the body substantially centrally

5 of said tape end connecting members; spring means normally returning each of said tapes to coiled conditions; ratchet means for holding said tapes in selected unwound lengths in opposition to said spring means; ratchet release means; and means operable externally of said body to operate said release means in pairs to permit return of the pair of tapes at one end of said body independently of the other pair of tapes.
